UNITED STATES PATENT OFFICE

2,550,577

RELAY CONSTRUCTION

Frank R. McBERTY, Mansfield, Ohio, assignor to
The North Electric Manufacturing Company,
Galion, Ohio, a corporation of Ohio

Original application July 29, 1940, Serial No.
348,222. Divided and this application March
6, 1946, Serial No. 652,335

9 Claims. (Cl. 200—104)

1

My invention relates, generally, to relay constructions and it has particular relation to the construction of relays for automatic telephone exchange systems.

This application is a division of my application Serial Number 348,222, filed July 29, 1940, which issued as Patent 2,396,332 on March 12, 1946.

Among the objects of my invention are: to reduce the wear on the armatures of the relay construction disclosed herein where the same contacts the glass rod stop member; to obviate the production of fine metal dust otherwise produced if the relatively soft metal armature were permitted to strike repeatedly the hard glass surface; and to improve the relay construction and lengthen the life thereof.

For a more complete understanding of the nature and scope of my invention, reference may be had to the following detailed description taken in connection with the accompanying drawings, in which:

Figure 1 is a view, in side elevation, certain parts having been broken away to more clearly show the details of construction, illustrating one embodiment of my improved relay construction assembled as a part of a line finder or connector link of an automatic telephone exchange of the relay type;

Figure 2 is an end view of the construction shown in Figure 1, certain parts being shown in section;

Figure 2A is a sectional view, similar to Figure 2, showing in more detail the arrangement of the magnetic circuit;

Figure 3 is a plan view, at an enlarged scale, showing the arrangement of one set of movable and stationary contact members;

Figure 4 is a longitudinal sectional view taken along the line 4—4 of Figure 3;

Figure 5 is a detail sectional view taken along the line 5—5 of Figure 4;

Figures 6 through 10 illustrate different steps in the manufacture of a contact finger for my improved relay construction;

Figure 11 is a plan view of a bank of movable contact members, two sets being shown, each set being arranged to be individual to a relay;

Figure 12 is a detail sectional view, at an enlarged scale, taken along the line 12—12 of Figure 11; and

Figure 13 is a top plan view showing how the armature is spaced slightly from the glass rod stop member by the metallic reed which carries the same.

2

Referring now particularly to Figures 1 and 2 of the drawings, it will be observed that the reference characters 10 and 11 each designate, generally, a relay construction. Each of these relay constructions may comprise what is known in the telephone art as a tens relay, ten of which are mounted in alignment to provide the tens relay of a line finder or connector link, as is disclosed in more detail in my copending application Serial No. 348,223, filed July 29, 1940, now Patent No. 2,415,437, issued February 11, 1947. Since the construction of the relays 10 and 11 is identical, only one of them will be described in detail herein.

15 As shown in Figures 2 and 2A of the drawings, each relay is provided with a magnetic circuit which may be that of an electromagnet having a broad pole piece with a suitable magnetic return. The toward pole piece may take 20 the form of a T and the return pole piece may have the form of an interfitting U member comprising side plates 12 and the back-bar 13.

The two-sided magnetic structure is designed to receive on each of its sides, groups of armatures whereby the groups of armatures are acted upon by substantially equal portions of the flux generated in the core and thereby respond in substantially equal acts to equal forces.

25 As will hereinafter appear, instead of employing two side plates 12 and a back bar 13, the side plates 12 may be integral with each other and provide a generally U-shaped configuration which can be mounted on a separate back bar or other support, as may be desired. Since the members making up the magnetic circuits as herein disclosed are formed of silicon steel, this alternate construction is preferable, in some cases, since it is then unnecessary to construct the back bar 13 of silicon steel. Instead, it may 30 be constructed of other cheaper material.

The T-shaped magnetic member which interfits with the U-shaped magnetic member comprises a pole piece 14 and a core 15. The core 15 comprises the stem of the T and around it is 35 positioned a winding or coil 16 of conventional design. The core 15 may be secured to the back bar 13 and the pole piece 14 by press fits, if it is not desired to provide for ready removal of the coil 16. If it is desired to permit ready removal of the coil 16, then the pole piece 14 should be arranged to be readily detached from the core 15 or the core 15 should be arranged to be 40 readily detached from the back bar 13.

The pole piece 14 is of such material and 45 dimensions with relation to the U-shaped mem-

ber, the core 15 and the coil 16 that the flux generated by the coil is as nearly as possible equally distributed between the two sides of the pole piece and throughout the length of each side.

It will be observed that air gaps 17 are provided between the ends of the U-shaped magnetic member formed by the side plates 12 and the back bar 13 and the ends of the top of the T-shaped magnetic member formed by the pole piece 14 and the core 15. These air gaps are preferably about $\frac{5}{32}$ inch long. However, these air gaps bear a certain necessary relation to the size and material of the armatures and their proximity to the pole piece, as will be fully described later.

With a view to accurately aligning the side plates 12 of the U-shaped magnetic member with the pole piece 14, clamp plates 20 are provided on opposite sides of the side plates 12 and are secured in position by means of screws 21 which are threaded into the ends of strut members, one of which is shown at 22. It will be observed that the strut members 22 serve not only to provide a clamping action between the upper ends of the clamp plates 20, but also that they serve to space them and the side plates 12 apart.

Positioned on top of the pole piece 14 and common to both of the relays 10 and 11 is an insulating block 23 which is secured in position by screws, one of which is shown at 24, which project through the pole pieces 14 and into the upper threaded end of a strut member 25, the lower end of which is threaded into the back bar 13. The insulating block 23 is preferably formed of mouldable material, such as a thermoplastic. Along the edges of the insulating block 23 are moulded anvil contact members 26 which form the stationary contact members of the relays. The term "anvil" is employed herein to characterize a contact member that is rigidly and firmly mounted and against which another contact member reacts in the manner that a blacksmith causes his hammer to strike his rigidly and firmly mounted anvil. As is shown more clearly in Figure 4 of the drawings, each of the anvil contact members 26 is provided with a reentrant portion 27 about which the material forming the insulating block 23 is moulded to securely grip the anvil contact members in position.

Referring again to Figures 1 and 2 of the drawings, it will be observed that the anvil contact members 26 are provided with extensions 26a, 26b, 26c, 26d, etc. The extensions 26a, 26b, 26d, etc. are arranged in staggered relation of decreasing lengths and their upper ends are turned outwardly as indicated at 28 and notched as indicated at 29. This staggered arrangement of the extensions is provided in order to facilitate connection thereto of paralleling conductors which can then be positioned in coplanar relation. As is described in detail in my copending application, referred to hereinbefore, corresponding extensions 26a of the relays 10 and 11 are connected in parallel circuit relation by a wire which is secured in the notched portions 29 by being spot welded therein.

It will be observed that the upper ends 28 of the extensions 26c are turned inwardly rather than outwardly as is the case respecting the other extensions. This construction is employed since these extensions are not paralleled with any other extension of any other relay in the link. In order to permit the conductors connected to extensions, such as the extensions 26c, with conductors arranged in coplanar relation-

ship, these extensions on the several relays are staggered by having the upper end portions 28 of different heights.

It will also be observed that the extensions 26a, 26b, etc., on one side of the insulating block 23 are offset with respect to the corresponding extensions on the other side. The purpose of this offset relationship will be presently apparent.

The anvil contact members 26 and their extensions are formed of good conducting nontarnishing material such as German silver. In the embodiment of the invention shown in the drawings they are 0.080 inch wide and $\frac{3}{32}$ inch thick. The lengths of course vary depending upon the length of the extension individual thereto.

Individual to each of the anvil contact members 26, there is provided a contact finger which is designated generally at 32. Each contact finger 32 comprises a metallic reed 33 in the form of round wire which has good electrical conducting quality and is highly resilient and corrosion resisting. I have found that stainless steel wire, known as 18-8, and having a diameter of 0.016 inch, is highly satisfactory for my purposes.

Mounted on the upper end 34 of each of the metallic reeds 33 is an armature 35 which serves not only to fix the metallic reed 33 on energization of the winding 16 but also it serves to conduct current between the reed 33 and the associated anvil contact member 26. It is noted that the armatures 35 bridge the associated air gaps 17. The armatures 35 are so mounted with respect to the adjacent edges of the pole pieces 14 that an air gap of 0.032 inch is provided therebetween. It is possible to increase this air gap to 0.053 inch but the smaller air gap is preferable. When the armature 35 has been moved into its alternate position on energization of the coil 16, there is provided a residual air gap between the armature 35 and the adjacent edge of the pole piece 14 of from 0.010 to 0.012 inch. It will then be apparent that the movement of the armature 35 from one position to another is about 0.020 inch.

The armatures 35 are formed of material which not only has good electrical conducting properties but also material which is magnetic. I have found that material known as Alleghany metal No. 4750 is entirely satisfactory for this purpose. Each of the armatures 35 is preferably about 0.478 inch long, about 0.080 inch wide and about 0.0429 inch thick.

The lower ends 33a of the metallic reeds 33 project beyond insulating support members 37. The insulating support members 37 are formed of the same material as the insulating block 23 and, as will hereinafter appear, the metallic reeds 33 are especially prepared so as to make certain that they will be securely held in the insulating support members 37 on completion of the moulding operation.

Referring to Figure 1 of the drawings, it will be observed that the projecting lower ends 33a, 33b, etc., of the metallic reeds 33 extend downwardly through the same distances. It will also be observed that the lower ends 33a, 33b, etc., on one side of the relay construction are offset with respect to the corresponding lower ends 33a, 33b, etc., on the other side. This arrangement is provided in order to permit the coplanar arrangement of cross connecting conductors between corresponding tens relays of adjacent links as is described more fully in my copending application, referred to hereinbefore. The cross connecting conductors are secured by suitable

means, such as welding, to the lowermost portions of the projecting lower portions 33a, 33b, etc. Since these projecting portions are staggered, the cross connecting conductors can obviously be arranged in a single plane, as described. Since the anvil contact members 26 are arranged in alignment with their respective contact fingers 23, the reason for the offset positions of the anvil contact members 26 on the opposite sides of the insulating block 23 will now be apparent.

The insulating support members 31 in which are moulded the metallic reeds 33 may be secured in position on the back bar 13 by means of screws 38. These screws also serve to carry support members 39 which are arranged to support conductor brackets carrying conductors extending underneath the relays 10 and 11. As is set forth in detail in my copending application, referred to hereinbefore, certain of the downwardly extending ends 33a, 33b, etc., of the metallic reeds 33, are arranged to be connected in parallel in their respective links, while the remaining downwardly projecting end portions are arranged to be cross connected as described.

As shown more clearly in Figures 3, 4 and 5 of the drawings, each of the armatures 35 is provided with an erosion resisting contact member 41 in the form of a short length of round wire. The contact member 41 is preferably formed of good conducting material which will resist erosion due to abrasion and arcing. I have found that round wire formed of palladium is satisfactory for this purpose. A wire having a diameter of 0.020 inch and a length of about 0.070 inch of this material is welded, as shown, across one face of the armature 35 to provide the contact engaging surface thereof.

Each of the anvil contact members 26 is likewise provided with erosion resisting material. As shown, this comprises an insert 42 in the lower end of each of the anvil contact members 26. The inserts 42 may be formed of palladium and are inlaid by conventional means in a strip of German silver from which the anvil contact members and their integral extensions are cut. The insert 42 is preferably about $\frac{1}{2}$ inch wide and about 0.010 inch thick. As indicated at 43, each of the inserts 42 is grooved intermediate its ends so as to provide two distinct points of contact engagement with the generally cylindrical contact member 41 carried by the armature 35. In the event that the alignment between the armature 35 and the anvil contact member 26 is not such as to initially cause both contact engagements to take place, it will be obvious that the armature 35 will be turned slightly due to the pull of the flux generated by the coil 16 so as to cause the two point contact engagement as described.

It is highly desirable that the armatures 35 associated with each side of each of the relays 10 and 11 be accurately aligned so that uniform air gaps are provided between them and the adjacent edges of the pole pieces 14. For this purpose, as shown in Figure 2 of the drawings, the metallic reeds 33 are so arranged that they tend to bias the armature 35 outwardly to a position beyond the normal open circuit position.

The stop member 44 of suitable, hard, rigid and non-hygrosopic material such as Pyrex glass, is positioned along the armature 35, and is so located that the inherent resilience of the metallic reeds 33 urges armatures 35 toward the glass rods 44. As shown in Figure 13, the arma-

ture 35 itself does not rest against the glass rods 44 but rather it is spaced slightly therefrom by the upper end portion 34 of the metallic reed 33. Since the reed 33 is formed of relatively hard metal, stainless steel, as compared with the armature 35, Alleghany metal, and further since it makes substantially only point contact with the glass rod 44, there is a minimum of wear and production of metal dust which would otherwise be the case if the armature 35 itself were permitted to strike the glass rod 44. The importance of this feature will be appreciated more fully when it is recalled that the armatures 35 are operated many millions of times during the life of the relay of the type here concerned.

The glass rods 44 are held in position by means of suitable non-magnetic clamp members 45 which are held in place by the screws 21. It is the common experience in apparatus of the types herein under consideration that the resting anvils upon which spring points, levers and armatures normally rest under more or less pressure are subject to various changes which alter the positions of the resting parts and delay or stop their operation. The metals and some insulating material used yield under the hammering of the return strokes of the parts and alter the position of rest and consequently the operating adjustment. Moisture is deposited upon the surfaces which affects the material chemically, or in the case of sudden lowering of temperature, may actually freeze the parts in their resting position; oxides and impalpable metallic powders form; dust accumulates; the moisture when present consolidates these extraneous materials into adherent scales or adhesive cements, the deleterious action of which is increased as the contacting surfaces are hammered down into close fitting surfaces. These effects disturbing to the operation, vary with temperature, moisture and frequency of operation and require a large factor of safety in the forces required to move the movable part from its resting anvil. In the course of a relatively short period, such parts require cleaning and in the meantime, increasingly frequent and irregular failures of operation may take place. The moving parts—armatures and reeds—in the invention here described, bear upon their resting anvils with slight force, merely enough to fix accurately the position of rest, and are intended to be operated upon by minimum attractive forces, since by these means the energy consumed by the device and the detrimental and destructive effects of the motion are reduced to a minimum and the speed of operation is increased.

The stop-rod 44 of Pyrex or equivalent glass, is straight, inflexible, unchanging under normal temperatures; it is not deformed by the impact of the parts resting upon it; it suffers no chemical change, accumulates no moisture or dust, it changes temperature slowly and does not freeze the armatures; and in no way injuriously affects the metal parts resting upon it. In fact, the operation of the armatures hundreds of millions of times, equivalent to the thousands of years of commercial operation, exhibits practically no alteration in the characteristics of operation. It must be assumed that the impact of the returning armature upon the glass rod transmitted through the projecting part of the upper end portion 34 of the reed 33 must expend in heat its energy of motion and must create some vibration; but it is found that the period of vibration is of such high frequency and so brief as to be

hardly detectable in a cathode ray oscillograph.

Not only do the glass rods or stop members 44 align the armatures 35 so that uniform air gaps are provided, but also they serve to prevent oscillation of the armatures 35 on the deenergization of the coil 16. As soon as the armatures 35 engage the stop members or glass rods 44 through the upper end portions 34 of the metallic reeds 33 they are immediately brought to rest without vibration or chattering.

It will be noted that leads 46 from the coil 16 are brought out and are connected to metallic reeds 47, which also extend through the insulating support members.

In Figures 6 through 12 are illustrated the steps involved in making up a set or bank of contact fingers 32. Of course, the sequence in which these steps are performed may be varied, the sequence that is set forth hereafter being one that has proven to be highly satisfactory.

The metallic reeds 33 of 18-8 stainless steel should be straight in order to permit assembly into the contact bank in such manner that no adjustments are required once the relay assembly has been completed. As shown in Figure 6, each metallic reed 33 is deformed as indicated at 49 intermediate its ends to provide a flattened portion. The maximum thickness of the flattened portion 49 is preferably about 0.012 inch. The flattened portion 49 is provided in order to prevent turning of the metallic reed 33 after it has been moulded in the insulating support member 37.

The end 34 is then positioned in a slot 50, Figure 7, in the armature 35. The slot 50 is slightly less in depth than the diameter of the metallic reed 33. With a reed of 0.016 inch diameter, the slot 50 has a depth of 0.014 inch, thereby leaving the reed to project above the surface of the armature 0.002 inch to facilitate welding, as will hereinafter appear, and to provide substantially point contact with the glass rod 44.

The armature 35 with the end 34 of the metallic reed 33 inserted in the slot 50 is then placed between the jaws 51, Figure 8, of a suitable press which are moved toward each other, as indicated by the arrows in order to deform the walls of the slot 50 about the end 34 of the metallic reed.

Next, as shown in Figure 9, the palladium wire contact member 41 is welded on to the outer end of the armature 35 on the side away from the end 34 of the metallic reed.

The required number of contact fingers 32, assembled as described, together with the necessary number of coil connectors 47, are assembled in a suitable mould and the insulating material is moulded in position about the flattened portions 49, as shown in the finished product illustrated in Figures 11 and 12.

It will be observed that two sets of contact fingers 32 for two tens relays form a unitary construction through the use of a single insulating support member 37, to both sets. Obviously, the contact fingers can be assembled in single sets, if desired. It will be noted that one end 52 of the insulating support member 37 is notched outwardly while the other end 53 is notched inwardly. This construction permits overlapping of the adjacent ends of adjacent insulating support members of adjacent tens relays so that a single screw can commonly support both of them.

In a preferred construction, insulating support member 37 is $\frac{1}{16}$ " wide. The metallic reeds 33

project above the support a distance of $1\frac{1}{16}$ ". They project below the insulating support 37 one-half inch. In a typical link assembly certain of the lower projecting portions 33a of the contact fingers 32 will be longer than others in order to provide for longitudinal connection therewith with respect to the link. The other downwardly projecting ends will be of the same length to facilitate cross connections between the links by conductors in coplanar relation as described.

After the contact fingers 32 have been moulded in the insulating support member 37, the armatures 35 are commonly positioned on one electrode 54, Figure 10, of an electric welder. A welding wheel 55 is then moved relative to the armatures 35 so as to successively engage the projecting portions of the ends 34 of the metallic reeds 33. On flow of current between the wheel 55 and the electrode 54 through the metallic reed and armature 35, the latter two are securely welded together as will readily be understood. The reason for having portions of the metallic reeds project above the armatures 35 in the grooves 56 therein will now be more clearly apparent.

Since certain further changes may be made in the foregoing described constructions and different embodiments of the invention can be made without departing from the scope thereof, it is intended that all matter contained in the above description or shown in the accompanying drawings shall be interpreted as illustrative and not in a limiting sense.

I claim as my invention:

1. In a multi-circuit controlling relay, the combination of an electromagnet, multi-contact armature means responding simultaneously thereto comprising a row of flexible wire reeds each anchored at one end, armature plates of magnetic material secured to the other ends of said reeds, contact means carried by said armature means for controlling individual circuits, and a common back-stop for said row of flexible wire reeds comprising a rod of insulating material extending transversely across the back side of said row of reeds, each of said reeds having a cylindrical rear surface and said back-stop rod having a cylindrical front surface, whereby the contact between each reed and said back-stop rod is the point contact of two cylindrical surfaces engaging each other substantially at right angles.

2. In a multi-circuit controlling relay, the combination of an electromagnet, a row of flexible wire reeds each anchored at one end adjacent to said electromagnet, individual armature plates of magnetic material secured to the other ends of said reeds, all of said armature plates and reeds responding substantially simultaneously to the energization of said electromagnet, individual movable contacts carried by said armature plates, stationary contacts adapted to be engaged by said movable contacts for multi-circuit control, and a common back-stop for all of the flexible wire reeds in said row comprising a glass rod extending transversely across the back side of said row of reed, each of said reed having a cylindrical rear surface and said back-stop rod having a cylindrical front surface, whereby the contact between each reed and said back-stop rod is the point contact of two cylindrical surfaces engaging each other substantially at right angles.

3. In a multi-circuit controlling relay, the combination of an electromagnet, a row of flexible wire reeds each anchored at one end in proximity to said electromagnet, individual armature plates

of magnetic material secured to the free ends of said reeds, all of said armature plates and reeds responding substantially simultaneously to the energization of said electromagnet, individual movable contacts carried by said armature plates, stationary contacts adapted to be engaged by said movable contacts for multi-circuit control, and a common back-stop for all of the flexible wire reeds in said row comprising a hard-wear resisting type insulating rod extending transversely across the back side of said row of reeds substantially directly in rear of said armature plates, whereby to absorb the return stroke inertia of said armature plates in their movement away from said stationary contacts without causing fore and aft flexure of their individual supporting reeds, each of said reeds having a cylindrical rear surface and said back-stop rod having a cylindrical front surface, whereby the contact between each reed and said back-stop rod is the point contact of two cylindrical surfaces of hard-wear resisting materials engaging each other substantially at right angles.

4. In a multi-circuit telephone relay of the class described, the combination of an electromagnet, multi-contact armature means responding simultaneously thereto comprising a row of flexible wire supporting reeds each anchored at one end, each of said reeds being of cylindrical cross-section, individual armature plates of magnetic material secured to the free ends of the reeds, all of said armature plates and reeds responding substantially simultaneously to the energization of said electromagnet, individual movable contacts carried by said armature means, a row of stationary contacts adapted to be engaged by said movable contacts for multi-circuit control, each of said armature plates having a slot therein extending longitudinally of its rear surface, the individual supporting reed associated with each plate being secured in said slot with a portion of its cylindrical surface protruding rearwardly from said slot to form a cylindrical stop surface, and a common back-stop for all of the flexible wire supporting reeds in said row comprising a wear resisting type insulating rod extending transversely across the back side of said row of reeds and arranged to be engaged by those portions of said reeds which protrude rearwardly from the slots in said armature plates.

5. In a telephone relay, in combination, a relatively small diameter flexible metallic reed fixedly mounted at one end, an armature plate of magnetic material relatively wide as compared to the diameter of said reed carried thereby at its other end with a cylindrical portion of the reed extending therefrom along the back side thereof, a movable contact carried by said reed, a stationary

contact adapted to be engaged by said movable contact, means for attracting said armature plate to move the armature plate and movable contact toward said stationary contact, and a cylindrical stop of relatively hard wear and corrosion resisting insulating material extending transversely of said armature plate and metallic reed and arranged to be engaged by said portion of said reed projecting from said armature plate to limit movement of said armature plate away from said stationary contact.

6. The invention, as set forth in claim 5, wherein the cylindrical stop is a round glass rod.

7. The invention, as set forth in claim 5, wherein the metallic reed is of stainless steel and the cylindrical stop is a round glass rod.

8. The invention, as set forth in claim 5, wherein the armature plate is formed of relatively soft material likely to become disintegrated if allowed to contact the stop, the reed is formed of relatively hard stainless steel capable of withstanding repeated impacts with the stop without disintegration, and the stop is a round glass rod.

9. In a telephone relay, in combination, a relatively small diameter flexible non-corrosive metallic reed fixedly mounted at one end, an armature plate of magnetic material relatively wide as compared to the diameter of said reed carried thereby at its other end, a movable contact carried by said metallic reed, a stationary contact adapted to be engaged by said movable contact, electromagnetic means for attracting said armature plate, and a stop of relatively hard wear resisting glass material extending transversely of said metallic reed and armature plate and arranged to be engaged by said metallic reed to position said armature plate with a minimum of chatter for subsequent reoperation with each de-energization of said electromagnetic means.
